United States Patent Office

Des. 204,319
Patented Apr. 5, 1966

204,319

HOLLOW CORNER PRISM

Donald E. Stewart, Arcadia, Calif., assignor to Electro-Optical Systems, Inc., Pasadena, Calif., a corporation of California

Filed Nov. 6, 1964, Ser. No. 82,505

Term of patent 14 years

(Cl. D57—1)

Fig. 1

Fig. 2

Fig. 3

Fig. 4

FIG. 1 is a top plan view showing a new design for a hollow corner prism.

FIG. 2 is a side view of the prism shown in FIG. 1.

FIG. 3 is a bottom view of the prism shown in FIG. 1; and

FIG. 4 is a perspective view thereof.

I claim:

The ornamental design for a hollow corner prism, as shown.
